UNITED STATES PATENT OFFICE

ALEXANDER E. JOHNSON, OF CHICAGO, ILLINOIS

ASTRONOMICAL APPARATUS

Application filed January 30, 1928. Serial No. 250,654.

My invention relates to astronomical apparatus.

One of the objects of the invention is to provide an apparatus by which the relative movements of astral bodies, particularly the earth, sun and moon may be indicated.

Another object of the invention is to provide an apparatus by which the eclipses of the sun and moon may be ascertained and indicated.

Another object of the invention is to secure the foregoing and other desirable results in a simple and expeditious manner.

In the accompanying drawings:

15 Fig. 1 is an elevation of an astronomical apparatus embodying my present invention;

Fig. 2 is a cross section on line 2, 2 in Fig. 1;

Fig. 3 is a plan view of the apparatus;

20 Fig. 4 is a view in plan at the line 4—4 of Fig. 1; and

Figs. 5, 6, 7, 8, 9 and 10 are views of details of construction.

Referring to the drawings, I show an apparatus having a base 1 on which is mounted the operating mechanism. This involves rotary supports 2 and 3, which are in different vertical planes, as by placing the support 2 below the support 3, whereby said supports

30 may rotate independently of one another.

The support 2 is mounted on a rotary member 4 and the support 3 on a rotary member 5, each of which members 4 and 5 are independently driven so as to turn at different

35 rates of speed. The support 2 carries an upwardly extending member 7 which is provided with a device 8 intended to represent the sun. This device 8 is adapted for adjustment on the support 7 in a vertical

40 manner. The support 3 is provided with an upwardly extending member 9 on which is a device 10 to indicate the moon, said device 10 being also vertically adjustable. Thus these

45 two rotary supports with their vertically extending carrying members will indicate the sun and moon and their rotation will indicate the movements of the sun and moon.

A central member 11 is also provided and on the top of this is a device 12 which indicates the earth. This central member 11 re-

mains stationary and occupies a central position so that the sun and moon revolve around it. Thus it will be seen that the sun and moon devices 8 and 10, respectively, may be rotated about the earth device 12, and may come into various positions with reference to said device 12 and with reference to one another.

Driving mechanism is provided by which these devices 8 and 10 may be revolved about the earth device 12 in accordance with the actual movements or orbits of the sun and moon relatively to the earth. Thus, since the sun apparently travels around the earth once in twenty-four (24) hours, the device 8 will travel around the device 12 in a given period

of time which will be considered twenty-four (24) hours. Also, since the moon travels around the earth in from twenty-four (24) hours and forty-five (45) to twenty-five (25) hours and two (2) minutes, the device 10 will be arranged to travel around the device 12 in this period of time relatively to the period of time taken by the device 8. Thus, as these devices 8 and 10 travel around the device 12,

the device 8 will lead the way and the device 10 will follow and each revolution will place these devices farther and farther apart until they are substantially opposite one another and then they will come closer, just as the sun and moon act in the heavens.

While the driving mechanism to accomplish this result could be varied, I show, particularly in Fig. 4, a driving mechanism comprising a hand lever 14 pivoted on a shaft 15 and having a spring controlled tooth 16 controlled by a pivoted arm or catch 17, the shaft 15 having teeth 18 cooperating with tooth 16, so that by pulling on lever 14 against action of springs 20, wheel 18 will be turned in an anti-clockwise direction (Fig. 4), after

which lever 14 may be released so that it will be drawn back to original or normal position and tooth 16 will pass over teeth 18 in the manner of a ratchet, leaving wheel 18 in turned or adjusted position. Shaft 15 also carries a gear 21 meshing with pinion 22,

which latter is connected with trains of gears 70 for driving the spur wheels 2^b and 3^b connected to the rotary supports 2 and 3, as shown in Fig. 7. A clock work 25 is also shown, be-

55

ing preferably connected with the aforesaid train of gears so as to time the hour and minute hands and regulate the speed of the mechanism. By means of the ellipse 7^b and springs 7^c the sun support 7 is moved back and forth towards the center of rotation so as to represent the orbit of the sun; and by means of ellipse 9^b and spring 9^c the moon support 9 is similarly moved back and forth to represent the orbit of the moon.

The sun support 7 is provided with a graduated portion 7^a (Fig. 8), the graduations 28 being to indicate the approximate days of the year, certain graduations being for months with intervening graduations which will represent fractions of months. Thus the sun 8 may be adjusted up and down and when this is done its position according to graduations will indicate the position of the sun, that is, its height in the horizon for the various times in the year, the sun as well known being highest in the summer and lowest in the winter and moving between the high and low points during the intervening months. Similarly, the moon support 9 has a graduated portion 9^a provided with graduations 30 (Fig. 1), arranged along an inclined slot 31. Three graduations are marked to indicate days in the moon's declination, the moon working farther from the sun or waxing, as it is called, for thirteen (13) and a fraction days and then working toward the sun and waning for another thirteen (13) and a fraction days. These marks or graduations 30 indicate thirteen (13) and a fraction days and so permit the moon device 10 to be adjusted in position accordingly.

The apparatus is also preferably provided with a sun dial 33 on which there are preferably four (4) series of concentric figures and letters. The outer series 34 represents days of the month from one (1) to thirty-one (31) inclusive. The next series 35 represents days of the week from Sunday to Saturday, inclusive. The next series 36 indicates the months from January to December, inclusive, and the innermost series 37 indicates years which may be selected as desired.

A series of rotating fingers or pointers 40, 41 and 42 are provided, being mounted centrally of the dial 33, the pointer 40 being for the outer circle 34 of days in the month, the next pointer 41 being for the next circle 35 for days in the week, and the other finger 42 being for the next circle 36 of months in the year.

These fingers or pointers 40, 41 and 42 are connected with the aforesaid train of mechanism driving the sun member 2 so that the fingers rotate as said support 2 rotates. The connection is such that the member 40 will move a distance of one (1) day in the circle 34 each time the support 2 makes a complete revolution, or it may be set each time the sun device 8 travels once around the earth device

12. This marks the period of the day. The finger 41 is so connected that it will also move the distance indicating a day in the circle 35, that is, from Sunday to Monday, or Monday to Tuesday, or the like, this movement of a day taking place each time the sun device 8 travels around the earth device 12 and also each time the pointer 40 moves one day's distance, as indicated by one of the numerals in circle 33. The other pointer 42 is so connected as to move one unit distance indicating a month, for each thirty one days, that is, for each thirty-one revolutions of the device 8 around the device 12 and the movement of pointer 40 thirty-one (31) numerals in circle 34. The figure 31 is selected, although some months are thirty-one (31) days and February is only twenty-eight (28) or twenty-nine (29) days, but this works out best in the long run, subject to slight correction, if necessary.

The device is also preferably provided with a dial 45 for the moon. This has an outer circle 46 divided into two halves, each half of which has numerals running to 13 and a fraction, about 13 $\frac{2}{3}$ in fact. A pointer or hand 47 is pivotally mounted at the center of the dial so as to cooperate with these figures 46. The inner dial 48 has numerals running up to 12 and a hand or pointer 49 centrally mounted cooperates with this inner dial or circle of figures 48. The pointers 47 and 49 are connected with the train of mechanism driving the moon support 3 so that the pointers revolve as the moon support and the moon device 10 revolve. The connection is such that the pointer 47 will move one numeral or unit each time the support 3 with the moon device 10 thereon rotates. The other pointer 49 moves one numeral or unit for each complete revolution of the pointer 47, the pointer 47 thus being an indicator of moon days constituting a moon month and the pointer 49 constituting an hourly indicator for the hours of the day.

The operation of the device will be as follows: The sun and moon devices 8 and 10 will be set close to one another to indicate the sun and moon in conjunction and the pointers 40, 41 and 42 will be adjusted for a day known to be a date at which the sun and moon will have this relationship and the pointers 47 and 49 will be set at zero. The sun device 8 will be adjusted on its support 7 according to the date selected on the sun dial 33 and the moon device 10 will be set in a zero position. The hand lever 14 will then be operated so as to energize the device and then said hand lever will be released. The mechanism will then run controlled by the clock 25, which will retard and make uniform its movement. The sun and moon devices 8 and 10 will then revolve around the earth device 12 and in this revolution will slowly become separated so that in time the devices 8 and 10 will be on opposite sides of

the device 12. At this time the mechanism is stopped and the device 8 adjusted on its support 7 according to the position the fingers 40, 41 and 42 indicate to be the time of year at which the apparatus has been stopped. The moon device 10 is also adjusted vertically on its support 9 according to the position of the moon, as indicated by the dials 46 and 48. When this adjustment is made sight will be taken through the apparatus looking through the slots in members 7 and 9 and if the devices 8, 10 and 12 are in alignment, it will be indicated that there will be an eclipse of the moon, because the earth device 12 will be in position between the sun device 8 and moon device 10. If these three devices are not in alignment there will be no eclipse of the moon and the operation of the apparatus will be resumed. When, during such operation, the members 8 and 10 come into position close to one another the apparatus is again stopped and the devices 8 and 10 adjusted vertically in accordance with the indications on the sun and moon dials 33 and 45, respectively. If after this adjustment devices 8, 10 and 12 are in alignment with device 10 between devices 8 and 12, there will be an eclipse of the sun because device 10 will be between earth 12 and sun 8. If there is no such alignment there will be no eclipse. The operation of the apparatus will again be resumed until members 8 and 10 are substantially opposite one another when the apparatus will be stopped again, and devices 8 and 10 adjusted in accordance with the readings on their dials. If the three devices are in alignment there will be an eclipse. If not in alignment there will be no eclipse. If there is an eclipse the date of the same will be indicated by the position of the hands or pointers on the sun dial 33. If there is no eclipse the operation of the apparatus will be again resumed until the devices 8 and 10 are close to one another and then they will be adjusted according to their dials, and if there is an alignment of the three there will be a sun eclipse, the date of which will be indicated by the position of the sun dial hands. In this way it will be seen that eclipses of both the sun and moon can be ascertained and the dates of the same found. The curved members 80 and 81 are for supporting certain star representations.

Some small adjustment of the moon dial is necessary and to this end a gear 51 is provided and four (4) arms 52, each of which has a finger 53 capable of fitting into the teeth of gear 51. This will permit adjustment of the moon dial for fractions of days.

It will be understood that changes and modifications may be made without departing from the spirit of the invention.

What I claim is:

1. An astronomical apparatus comprising sun, moon and earth devices, and means for causing the rotation of the sun and moon de-

vices around the earth and means for adjusting said sun and moon devices transversely with reference to their orbits.

2. An astronomical apparatus comprising sun, moon and earth devices, means for causing the sun and moon devices to travel around the earth devices, said means being adapted to move said sun and moon devices toward and from the earth device during their rotation around the same, and means for adjusting the sun and moon devices transversely of their orbits.

3. An astronomical apparatus comprising sun, moon and earth devices, and means for causing the rotation of the sun and moon devices around the earth and also means for obtaining the adjustment of said sun and moon devices transversely with reference to their orbits, and means for indicating the time of year, said means being inter-connected for operation as the sun and moon devices travel around the earth device.

4. An astronomical apparatus comprising sun, moon and earth devices, and means for causing the rotation of the sun and moon devices around the earth and also for obtaining the adjustment of said sun and moon devices transversely with reference to their orbits, and means for indicating the position of the moon, said means being inter-connected for operation as the moon device revolves around the earth device.

5. An astronomical apparatus comprising a central earth device and two rotary supports, one carrying a standard for a sun device and the other carrying a standard for a moon device, means for rotating said supports in accordance with the apparent orbits of the sun and moon around the earth, said sun and moon devices being adjustable on their supporting standards transversely of the direction of rotation, a day indicating device comprising rotary fingers for indicating the days of the year, and mechanism for actuating said fingers as the sun support rotates, and a day indicating device for the moon comprising rotary fingers connected to rotate as the moon device rotates.

6. An apparatus of the class specified having a centrally arranged device for indicating the earth and a pair of rotary members carrying supports on which are mounted devices representing the sun and moon, the sun device being adjustable on its support and its support being provided with marks or graduations to indicate dates of the year and the moon device being adjustable on its support and its support being provided with marks or graduations to indicate the position of the moon in declination, means for rotating said supports at speeds proportionate to the apparent rotation of the sun and moon around the earth, dial devices for indicating the time of year, said devices being connected with the sun rotary support to oper-

ate with the same and to indicate the time of year for any position of the sun and moon dial devices connected with the rotary support for the moon and arranged to indicate the position of the moon in declination.

5 In witness whereof, I hereunto subscribe my name this 29th day of December; A. D. 1927.

ALEXANDER E. JOHNSON.
